UNITED STATES PATENT OFFICE.

FREDERICK J. HOYT, OF CHICAGO, ILLINOIS.

MINING-MILL.

No. 806,145.

Specification of Letters Patent.

Patented Dec. 5, 1905.

Application filed June 9, 1902. Serial No. 110,813.

To all whom it may concern:

Be it known that I, FREDERICK J. HOYT, a citizen of the United States, residing at Chicago, in the county of Cook and State of Illinois, have invented certain new and useful Improvements in Mining-Mills, of which the following is a specification, reference being had therein to the accompanying drawings.

My invention relates to an improvement in placer-mining and to that class of placer-mines wherein the gold is found coarse, fine, and floured and wherein also the gold from various causes has become oxidized, rusty, or otherwise by nature placed in a condition not to be promptly absorbed and taken up by quicksilver or when it is in too fine and floured a condition to gravitate and come in contact with the quicksilver or has by its condition no affinity for quicksilver, and therefore cannot be saved if it does come in contact therewith.

It is a well-known fact that the gold in a placer-bed has only therein a certain percentage that is clean and bright, free from all oxidids and rust, and which is attracted by quicksilver. While this is immaterial as to coarse gold, which can be caught in an ordinary sluiceway with riffles therein, that class of gold is only a small percentage of the values that can be saved if the finer gold can be cleansed and the oxidation and rust removed, quicksilver used, and the fine flour-gold caught which is too fine and light to gravitate. In other words, a placer-bed that by hydraulic sluicing would yield in value from twenty cents to seventy-five cents per cubic yard may, if all the values therein are saved, yield from five dollars up per cubic yard. The two important factors necessary to save all values in either placer or quartz mining are, first, to place the gold in a clean bright condition, so that its affinity for quicksilver will be free to act, and, second, to pass the pulp through a mill in which the gold in the pulp shall by mechanical devices be forced to come in contact with quicksilver. When these two essential points are gained, an absolute certainty of saving all the values is obtained. Another necessary adjunct is the ability to handle through this apparatus a large amount of material at a nominal cost per ton or yard.

The objects of my invention are, first, to handle a large amount of gold-bearing sand and gravel in such a way that the cost of operation may be small. This I accomplish by running the material in a continuous flow from the

feeding at the bank on to the head of the sluice to the tail-race without any delay or detention, and, second, to extract and save all the gold during its progress in its run over the apparatus. To accomplish these objects, I use a combination of a chemical sluiceway and a quicksilver device, in which sluiceway the chemical action of dissolving and scouring occurs and in which the quicksilver-machine catches the gold after it has been cleansed and brightened.

My invention is illustrated in the accompanying drawings, in which—

Figure 1 and Fig. 1^a show a longitudinal elevation of the entire plant; Fig. 2, a rear end elevation of a tail-screen and driving mechanism, and Fig. 3 a plan of an amalgamating device.

Referring to the drawings, A is a shaking-screen resting on a framework a', so constructed as to give the screen an inclined position, and directly beneath is placed sluiceway A' and a riffle-sludge A². The screen is operated by eccentric a³ and rod a¹⁰. The screen runs across sluiceway A', and the latter may be of any desired length or width; but preferably it is about two hundred feet from their united head to the amalgamating device and five feet wide. The sand and gravel carrying the gold are elevated by buckets or belt up to and discharged onto the screen A. The coarse gravel is discharged over the screen onto the sluice A², provided with riffles and over which the gravel is carried by force of water. On shaft a⁵ is a header over which buckets are discharged; a⁶, the elevating-buckets; a⁷, the pulleys for driving buckets, and a⁸ the header over which the buckets are turned.

At the head of the screen A and the sluiceway A' is located a tank C, which carries a chemical solution. From this tank leads a pipe c¹, controlled by a cock a⁴ and which connects with a perforated pipe c², extending across the head of the sluiceway A' and adapted to spread the solution over the entire surface of the latter. Cyanid of potassium is the preferred chemical solvent, which may be weak or strong, as the circumstances demand.

B is an amalgamating device which in the form shown constitutes the principal subject of my Patent No. 686,300 of November 12, 1901, and need not, therefore, be described now with great particularity. It is sufficient to say that it consists chiefly of a series of inclined copper plates b' for conducting a flow

of ore, said plates interspersed with half-cylinder troughs b^2 , each holding a body of live quicksilver, smooth copper cylinders b^3 revolving in said quicksilver in the direction 5 of the flow of the ore and over which plates and cylinders the pulp and solution pass from the sluiceway A' , and a final half-cylinder b^4 , having revolving fingers b^5 thereon to prevent any loss of quicksilver, said fingers and 10 rotating cylinders driven by a common gearing b^6 .

H is the end revolving screen. It is made of wire, preferably one-hundred-mesh fine or finer, if desired, preferably five feet wide and 15 in the form of an endless belt. It is rotated by a series of front sprocket-wheels h' , fastened on its under side to sprocket-chains h^2 , and is carried over and around a tank K of suitable size. At the corners, on both sides 20 of the tank K, are placed grooved rollers i , on which the sprocket-chains run and by which the screen is supported and guided. The end of the sluiceway A' projects over the top of the screen H a foot or more, as desired. Fig. 25 2 is a general view of said tail-screen, representing any width, showing but two sprockets and chains for convenience, one on each end, such as would be used on the narrower widths.

A tank K is placed underneath the screen 30 H and catches the solution from sluiceway A' , the screen revolving around the tank. Straight pipes c carry the solution back from the tank K to tank D, from which it is pumped up to tank C and run over again. Pipes d 35 carry part of the solution down from tank K to zinc boxes g , into which the dissolved gold is precipitated as the solution percolates up through the same, and from these boxes the solution thus stripped of the gold is led from 40 box to box and finally back to tanks E, where it is regenerated and used again. A pipe L on the nose of the screen and perforated pipe M have functions hereinafter described.

The shaking of the screen A cuts off the 45 coarse gravel and allows only the fine sand and gravel—say from one-half inch in size down—to pass through it into the chemical sluiceway A' , the coarse material running down this inclined shaking-screen and falling 50 off into the outside sluice A^2 , where water floats it down over riffles placed in said outside sluice. The riffles catch and save any nuggets of one-half inch or larger of gold that may be in the placer-bed. The material 55 from one-half inch in size to finer sizes passes through the screen and falls onto the sluiceway A' . The solution discharged from the perforated pipe c^3 picks up and carries forward the sand and gravel as fast as it falls 60 through the shaking-screen A. The cyanid solution as fast as it comes in contact with any gold there may be in the pulp attacks it at once, and if very fine or floured the gold is dissolved before it reaches the quicksilver mill. During its passage down the two hun-

dred feet of sluiceway A' any gold contained in the sand that is too coarse to have been fully dissolved has been sufficiently attacked by the cyanid of potassium or other chemical solution used to remove all rust or oxidation therefrom and is then in the very best condition to be amalgamated by the quicksilver apparatus, to which it is carried by the downward flow of the solution. The gold having been cleansed by the chemical solution and now having an unobstructed attraction for the quicksilver is readily caught on this machine, as contact therewith is absolutely certain while the pulp is passing over the revolving cylinders. The pulp or sand 70 and gravel after passing over the quicksilver-machine goes forward over a continuation of the sluiceway—say ten or fifteen feet—and onto the revolving screen H. The sand, gravel, and the solution after the heavy gold has been 75 extracted and saved by the quicksilver-mill travel forward onto this revolving screen, through which the solution carrying the dissolved gold passes into the tank underneath. The remaining sand and gravel are carried 80 forward by the revolving screen to the point where the latter turns over the sprocket-wheels h' , when the pulp is automatically dumped onto the tail-race A^3 . It is then carried forward by water fed from an elevated 85 tank F, placed at this point and having a perforated pipe L discharging the water directly onto the nose of the screen and which washes all sand and gravel off the screen onto the tail-race and carries it forward to any point 90 desired for dumping. From this same tank F is run a small half-inch pipe M, crossing the screen at a point one or more feet back of the sprocket-wheels, which pipe is perforated and throws a spray onto the sand and 95 gravel and washes off and into the tank underneath the screen any of the chemical solution carrying the dissolved gold that may adhere to the same after the main solution leaves 100 it. All the pipes herein referred to are provided with stop-cocks, so that the flow of water and of the solution can be regulated or entirely cut off. It is clear that with the buckets or belt dumping onto the head of the sluice ten or fifteen pounds of sand and gravel at a time, 105 which is at once carried forward with two or three gallons of the cyanid solution from the tank C through the perforated pipe c^3 , this 110 solution has a chance to work only upon the gold which may be in this small amount of sand and gravel and continues with it until it reaches the revolving screen H, when it falls into the tank K below. Consequently the solution will not exhaust itself, not take up but a small percentage of the gold it has the capacity of taking up. Instead, therefore, at 115 this time trying to precipitate the solution with a reagent the tank K under the revolving screen is allowed to fill up with the solution to near its capacity, which precipitates to the 120

125 130

bottom any fine sand that may have passed with it through the screen. The solution from the tank K is then carried by gravity back beneath the sluice to the head of the same and discharged in a tank D, from which it is pumped to the upper tank C and then run over the sluice again. Thus this solution may be run ten or fifteen or more times until it has shown that its strength has been greatly diminished by the amount of gold it has dissolved. Then the upper continuous pipe *c* is closed and the pipes *d* below are opened. The solution then passes down and through the zinc boxes *g* from one to the other and in each of which gold may be precipitated. The weakened solution passes back from the zinc boxes through pipes *d* into forward tank E and is settled, regenerated, and pumped up above and used again.

20 I do not wish to be confined to any particular chemical, as there are several that may be used in this way, nor do I wish to be confined to this particular form of amalgamator or to the use of any amalgamator so far as the 25 coarse gold is concerned after the fine and floured gold has been dissolved, which may be caught on riffles in the sluiceway.

It will be seen that my invention is adapted to treat other ores than gold.

30 What I claim is—

1. In a mining apparatus, the combination in one structure of a shaking-screen, a chemical sluiceway, both inclined, the latter placed directly under the said screen, and both joined 35 at their heads at the point of ore and chemical-solution supplies, an amalgamating apparatus forming a part of the same structure and receiving the run both from the said screen and the sluiceway, said sluiceway having an extension beyond the amalgamator, a revolving tail-screen at the end of said extension, a tail-tank for receiving the solution, over which the screen revolves, receiving-tanks under the head of the machine, return-pipes from said 40 tail-tank to the head-tanks, zinc vats on the line of said pipes in which the solution is precipitated on its way back to the head, and pumping means to pump the solution from said head tank or tanks back to the original 45 supply-tank, whereby a continuous constant operation of the mill and a continuing circulation of the solution around the mill are obtained, substantially as described.

2. The combination of a screen and chemical sluiceway having its head beneath the screen, with an amalgamating device on which the said sluiceway discharges, an extension of the sluiceway beyond the amalgamating device, a revolving screen at end of said extension, a receiving-tank for the solution under said screen, a water-tank above said screen, and pipes leading onto said screen from the tank above, to wash the screen free from the solution and to carry the tailings beyond said

screen to place of discharge, substantially as 65 described.

3. The combination of an inclined shaking head screen and a sluiceway having its head beneath the screen, both leading from the ore-supply, a tank for a chemical solution for dissolving the ore at the head of said screen and sluiceway, a distributing, perforated pipe for spreading the solution over said sluiceway, and at the opposite end of said sluiceway, a receiving-tank for the solution, a revolving 70 screen for the tailings, a pipe system from said receiving-tank to end tanks under the head of the shaking-screen and the sluiceway, said end tanks, and pumping means to pump the solution back up to the said chemical tank, substantially as described.

4. In a mining apparatus the combination with a shaking-screen on which the material to be treated is first thrown, of an inclined sluiceway receiving the material from said screen 85 at its head, a tank of cleansing and dissolving solution placed at the head of said sluiceway, means for feeding the same to the sluiceway simultaneously with the ore, a tank placed at the lower end of said sluiceway to 90 receive the said solution and the dissolved and cleansed ore, a third regenerating-tank, and a pipe leading direct from said second tank to said regenerating-tank, substantially as described.

5. In a mining apparatus the combination with a shaking-screen on which the material to be treated is received, of an inclined sluiceway to receive the material from said screen at its head, a tank of cleansing and dissolving solution placed at the head of said sluiceway and means for feeding the same to the sluiceway simultaneously with the ore, a revolving screen and a tank placed at the lower end of said sluiceway, a third tank for regenerating 100 placed under the first tank at the head of the machine, and a pipe connection from said second tank to the third tanks, substantially as described.

6. In a mining-mill, a main sluice and an auxiliary sluice, means for feeding ore to said sluices adapted to distribute fine ore to the former and coarse ore to the latter, means for distributing over the fine ore a chemical solution adapted to cleanse and dissolve the 115 same, means for distributing water over the coarse ore, an amalgamator adapted to catch the cleansed fine ore, riffles adapted to catch nuggets from the coarse ore, means for separating the saturated solution from the tailings and for disposing of said tailings, a tank for receiving said solution, means for redelivering the solution freed from metal, and means for connecting the receiving-tank with either of said redelivering means, substantially 120 as described.

7. In a mining-mill the combination of a sluice, a screen at the head of said sluice,

means for feeding ore through the screen to the sluice, means for depositing on the sluice simultaneously with the ore a chemical solution adapted to scour and dissolve said ore, 5 an amalgamator adapted to catch the cleansed ore, a tank to receive said solution, means for redelivering the solution freed from metal, and means for connecting the receiv-

ing - tank with either of said redelivering means, substantially as described. 10

In testimony whereof I affix my signature in presence of two witnesses.
